MACHINE FOR CUTTING SHEET METAL

Anders Ingemar Knutsson Slettengren, Goteborg,
Sweden, assignor to Verkstads-A. B. Haldex,
Halmstad, Sweden

Application January 27, 1947, Serial No. 724,497
In Sweden February 6, 1946

3 Claims. (Cl. 74—38)

1

The invention refers to such machines for the cutting of sheet-metal or similar materials, wherein the cutting tool is actuated by a toggle-joint provided with two links, which are pivoted, the one about a fixed pin and the other about a pin on the tool holder, said links being adapted to have an oscillatory transverse movement imparted thereto in a plane extending at right angles to their axes of oscillation, which movement is produced by means of a connecting rod or the like actuating the intermediate link pin of the toggle-joint. In known machines of this type, the fixed point of the toggle-joint is adapted to be shifted in two extreme positions, i. e. one working position, wherein the tool holder moves so that the edges of the cutting tools are operating relatively near to one another, and an idle position, wherein the edges of the cutting tools are operating at a greater distance from each other, so that the work piece can be freely introduced between the edges of the tools. Said shifting is preferably effected by an adjustment of the fixed pin of the link system, which pin is eccentrically mounted, whereby the fixed link pin may be caused to take up an upper and a lower position.

In the cutting of sheet-metal of varying thicknesses and different materials, it will be found desirable to control the length of stroke of the movable tool and the number of strokes thereof within certain limits. In a toggle-joint of the type in consideration, such control may be provided by varying the magnitude of the oscillatory transverse movements of the links toward both sides from the plane extending through the two outer link pins. Preferably, the movement is then adjusted so that the links are caused to swing symmetrically on both sides of said plane, in the one case, and substantially on one side of said plane in the other case. The transverse movement attacking the intermediate pin of the links is assumed to proceed with a constant amplitude and frequency. In the first case, a resulting movement of the tool is obtained, which is distinguished by a small stroke at a certain oscillatory frequency, whereas in the other case a greater stroke of the tool is obtained at a frequency half as great as that in the former case. In the machines as previously known, said conditions of motion have been obtained by the fact that the intermediate link pin of the links would be actuated by a connecting rod, the other end of which would have a rotary movement imparted thereto from an eccentric rotating about a rigid shaft, and the length of which would be varied

2

in any suitable manner. The same effect may also be obtained by setting the axis of rotation of the eccentric to varying distances from the plane extending through the outer link pins of the toggle-joint. In both of these cases, separate means must be provided to render possible the shifting of the length of stroke of the cutting tool and the shifting of the fixed point of the toggle-joint into its upper and lower positions respectively.

The present invention relates to a simplified means for the shifting of the length of stroke, and is principally distinguished by the fact that the fixed link pin is fixedly adjustable into various positions displaced transversely of the direction of movement of the tool holder, in a manner such that the plane extending through the two outer link pins may be adjusted to different distances from the extreme positions of the intermediate link pin.

The invention will be described more closely with reference to the accompanying drawings.

Figs. 1 and 2 illustrate diagrammatically two different working positions of the transversely adjustable link point.

Fig. 3 shows a toggle-joint in longitudinal section.

Fig. 4 is a sectional side elevation on line 4—4 of Fig. 3.

30 Rotatably arranged about the stationary shaft 1 of the driving motor is an eccentric with the centre point 2 and the radius R. From here the motion is transmitted over the connecting rod L to the intermediate link point of the toggle-joint, said link point having its extreme positions 3, 4 at the distance of 2R from each other. The upper fixed link point is designated by 5, and 6 denotes the lower, vertically guided link point in its lowermost position, whereas 7 designates this latter link point in its uppermost position. The points 6 and 7 constitute the end points of the movement of the cutting tool in its working position. According to Fig. 1, the intermediate point of the toggle-joint moves to varying distances from the plane extending through the points 5 and 6. As a result, a relatively long working stroke 6—7 and a very small additional stroke 6—9 of the tool holder are obtained. The fixed link point 5 is eccentrically mounted, and may thus be moved to the point 8 by a turning movement of the corresponding journal, so as to cause the whole toggle-joint to be raised, so that the tool holder will move at a greater distance from the corresponding stationary cutting tool (not shown). The tool

then operates in an idle position, and work pieces may be introduced between the cutting tools.

Fig. 2 shows the fixed link point as shifted into a position 5', which has been attained by a continued turning movement of the eccentrically positioned journal. The position is preferably adapted so that the distance between the extreme position 6 of the movable outer link point and the alternative positions 5 and 5' of the stationary link point is the same in both cases. At the same time, the fixed link point will be displaced laterally with respect to the other unchanged parts of the system, whereby the plane between the outer points 5' and 6 of the toggle-joint may be set into a symmetrical position relatively to the extreme positions 3' and 4' of the oscillating link point, which latter positions are fixed relatively to the plane extending through 5 and 6. Hereby a shorter working stroke of the tool holder is obtained, which is now caused to move between the points 6 and 7' at a stroke frequency which is doubled as compared with the conditions in Fig. 1.

The toggle-joint consists in one upper link 20 journaled on an upper link pin 10 over a bushing 21 and one lower link 22 pivotally connected to a tool-holder 23 by means of a link pin 24. The links 20 and 22 are connected to each other by an intermediate link pin 25, the lower link 22 being journaled on the pins 24 and 25 by bearings 26 and 27, respectively. At the lower end of the tool-holder 23 there is a shear tool 28 mounted by any common attaching means 29.

Oscillating movement is imparted to the intermediate link pin 25 by an eccentric mounted on a stationary driving shaft 31 and generally referred to by the reference numeral 30. The eccentric has its center of rotation in point 1 eccentrically positioned relative to the center 2 of an eccentric disc 32 in an eccentric strap 33 and provided with a ball-bearing 34. The eccentric strap 33 is connected to the intermediate link pin 25 by an eccentric rod 36 which is forked at the link end to form lugs 31 engaging the pin 25 over bushings 38.

The upper link pin 10 is rotatably mounted in the opposite walls 41 and 42 of the mechanism casing 40 by an aligned rear shaft end 11 and a front shaft head 12 of the pin shaft 10 which is eccentrically arranged relative to its journals 11 and 12. At the outer end of the shaft head 12, there is a handle 17 pivoted about a pin 18 against the compression force of a spring 19 anchored in the head 12. By means of the handle 17, the link pin 10 can be rotated and fixed in any one of three positions 5', 5 and 8 by snapping in the handle 17 into one of the recesses 14, 15 and 16, in the casing wall 42.

The position occupied by the handle 17, as shown in Fig. 4, corresponds to the position 5' indicated in Fig. 2, providing for the tool-holder 23 two equally large strokes per revolution of the driving shaft 31. By simply shifting the handle 17 to recess 15, the single stroke operation of Fig. 1 will be obtained. If, however, the handle 17 be swung to recess 16 corresponding to position 8 of Figs. 1 and 2, the tool-holder 23 will

be lifted out of operating position and the tool will not cut but permit a work-piece to be inserted or removed, as the case may be.

The advantage of the invention primarily resides in that the raising of the cutting tool and the shifting of the stroke thereof may be effected by means of the same operating lever. Moreover, the invention highly simplifies the shifting of the length of stroke as such shifting may be effected by a single manipulation even during the operation of the machine. The invention also provides for a simple and condensed assembly of the shifting mechanism within a closed housing.

What I claim is:

1. In a machine for cutting sheet-metal and similar materials a toggle-joint arrangement comprising in operation two links, one stationary link pin, one intermediate link pin and one movable link pin, said movable link pin being connected to a tool holder arranged to reciprocate rectilinearly, driving means connected to said intermediate link pin to oscillate the same between extreme positions transversely of the direction of movement of said tool holder, one of the links being pivoted about said stationary and said intermediate link pins and the other link being pivoted about said intermediate and said movable link pins, said stationary link pin being movable into at least two positions transversely displaced relative to the direction of movement of the tool holder, and both of said positions being at a distance from a given common remote extreme position of said movable link pin equal to the maximum distance between the stationary and movable link pins, the plane extending through the axes of said stationary link pin when located in at least one of said positions and of said movable link pin passing between said extreme positions of the intermediate link pin, and locking means for fixing said stationary link pin in either of said transversely displaced positions.

2. Arrangement as claimed in claim 1, characterized in a shifting device, said stationary link pin being secured to said shifting device, and said shifting device being capable of moving said stationary link pin into said at least two positions and into a position longitudinally further apart from said common extreme position of said movable link pin than said two positions, the said locking means fixing said stationary link pin in either of all said positions.

3. Arrangement as claimed in claim 2, in which said shifting device is an eccentric.
